KNIFE HANDLE

Carlos Miller, Nogales, Ariz.

Application December 4, 1950, Serial No. 198,999

1 Claim. (Cl. 30—332)

1

This invention relates to a handle designed to hold tightly in place a small blade to provide a very simple sharp utility knife utilizable in homes, offices, and shops.

The primary object of this invention is to provide a knife handle consisting of two plates with a simple means for removably retaining the plates together so that a small blade can be frictionally retained between the plates and extend from one end thereof. The means securing the plates together prevents endwise as well as longitudinal relative movement between the plates, so that the blades can be retained at all times in a fixed position. The handle is further constructed in such a manner as to permit pressure of the fingers on opposite longitudinal edges of the handle so that the plates making up the handle can be readily separated for the removal and replacement of the blades.

These, together with various ancillary objects and features of the invention which will later become apparent as the following description proceeds, are attained by the device, a preferred embodiment of which has been illustrated, by way of example only, in the accompanying drawings, wherein:

Figure 1 is a perspective view of the device;

Figure 2 is a longitudinal sectional view taken substantially in the plane of section line 2—2 of Figure 1;

Figure 3 is a transverse sectional view taken substantially in the plane of section line 3—3 of Figure 1;

Figure 4 is a sectional view taken substantially in the plane of section line 4—4 of Figure 2;

Figure 5 is a plan view of one of the plates; and

Figure 6 is a plan view of the other plate.

Specific reference will now be made to the drawings. In the several views, in the accompanying drawings and in the following specification, similar reference characters indicate corresponding elements throughout.

The handle of the present invention is generally indicated at 10 and includes a first elongated metallic plate 12 and a second elongated metallic plate 14 of approximately the same dimensions. Adjacent the upper end 16 of the first plate, the longitudinal edges 18 and 20 are provided with lateral, oppositely extending lugs 22 and 24, while the bottom edge 26 of the plate is provided with a longitudinal extension 28 adjacent the longitudinal edge 18, as shown clearly in Figure 5. The longitudinal edge 18 of the plate is further provided with a finger-engaging cut-out portion 55

2

30 and intermediate the upper and lower ends of the plate a detent 32 is provided. The second plate 14 includes an upper end 34, longitudinal edges 36 and 38, and a lower end 40 including a longitudinal extension 42 adjacent the longitudinal edge 38. The longitudinal edge is provided with a finger-engaging cut-out portion 44 and intermediate the upper and lower ends of the plate the same is provided with a recess 46.

10 When the plates are assembled together, a small utility blade 48 is positioned between the plates and extends out of the upper ends 16 and 34 of the plates, as shown clearly in the drawings. The lateral lugs 22 and 24 are bent toward each other to embrace the longitudinal edges 36 and 38 of the second plate 14 and secure the upper ends of the plates together to apply frictional pressure to retain the blades 48. The longitudinal extensions 28 and 42 are bent around the lower edges 40 and 26 of the plates 14 and 12, respectively, to prevent relative longitudinal movement between the plates. The detent 32 is yieldingly received in the recess 46. Finger pressure on the longitudinal edges 20 and 36

15 of the plates 12 and 14 through the finger-receiving recesses 30 and 44 will urge the detent 32 out of the recess 46 and permit the two plates 12 and 14 to slide free of each other whereupon they may be separated to remove and replace the utility blades 48. It is evident, therefore, that the handle of the present invention is simple in construction and design, inexpensive, and easy to manipulate for the retention and removal of a utility blade.

20 In view of the foregoing description taken in conjunction with the accompanying drawings, it is believed that a clear understanding of the device will be quite apparent to those skilled in this art. A more detailed description is accordingly deemed unnecessary.

25 It is to be understood, however, that even though there is herein shown and described a preferred embodiment of the invention, the same is susceptible to certain changes fully comprehended by the spirit of the invention as herein described and within the scope of the appended claim.

30 Having described the invention, what is claimed as new is as follows:

35 A knife handle comprising separate and individual first and second elongated perfectly flat plates having upper and lower ends, means for removably retaining the plates together to frictionally hold a blade between and extending from their upper ends, said means including a pair of

longitudinally spaced lugs on opposite longitudinal edges of said first plate and situated adjacent to the upper end of said first plate, said lugs being bent inwardly toward each other and providing assembling and retaining hooks releasably embracing the upper end of said second plate, a longitudinal extension at the lower end of said first plate and adjacent to one longitudinal side, said extension being bent and hooked over the lower end of said second plate and a longitudinal extension at the lower end of said second plate, adjacent to the opposite longitudinal edge, said extension being bent into hook-shape and releasably engaged over the lower end of said first plate said bent extensions serving to prevent relative longitudinal movement of said plates, a detent in said first plate intermediate the upper and lower ends yieldably seatable in a correspond-

ing recess in said second plate, finger-receiving cut-out portions in said longitudinal edges of said plates adjacent said bent extensions, whereby pressure may be applied to move the detent out of the recess and to thus assist in the separation of the plates.

CARLOS MILLER.
